[57] CLAIM

The ornamental design for a shield for thong panty, as shown and described.

DESCRIPTION

FIG. 1 is a perspective view of a shield for thong panty, showing my new design; the broken line showing of a thong panty is for illustrative purposes only and forms no part of the claimed design;

FIG. 2 is a top plan view thereof;

FIG. 3 is a bottom plan view thereof;

FIG. 4 is a left side elevational view thereof, the right side elevational view being a mirror image;

FIG. 5 is a front elevational view thereof; and,

FIG. 6 is a rear elevational view thereof.
